UNITED STATES PATENT OFFICE.

FRANK SHUMAN, OF PHILADELPHIA, PENNSYLVANIA, ASSIGNOR TO PENNSYLVANIA
WIRE GLASS COMPANY, A CORPORATION OF PENNSYLVANIA.

DESIGN FOR SHEET-GLASS.

43,349.

Specification for Design.

Patented Dec. 17, 1912.

Application filed August 19, 1910. Serial No. 578,071. Term of patent 14 years.

To all whom it may concern:

Be it known that I, FRANK SHUMAN, a citizen of the United States, and a resident of the city and county of Philadelphia, State of Pennsylvania, have invented a new, original, and ornamental Design for Sheet-Glass, of which the following is a specification, reference being had to the accompanying drawing, forming part thereof, and

which shows a plan view of my improved design for sheet-glass.

I claim:

The ornamental design for sheet glass, as shown.

FRANK SHUMAN.

Witnesses:

S. A. BLEND,
CONSTANTINE SHUMAN.
